UNITED STATES PATENT OFFICE.

HOMER STEWART, OF BEAVER FALLS, PENNSYLVANIA, ASSIGNOR OF THREE-FOURTHS TO WALTER M. LAWRENCE, OF WASHINGTON, DISTRICT OF COLUMBIA, AND SAMUEL M. LAWRENCE, OF BEAVER FALLS, PENNSYLVANIA; SAID SAMUEL M. LAWRENCE ADMINISTRATOR OF WALTER M. LAWRENCE, DECEASED.

STOP-OFF VALVE FOR GAS.

SPECIFICATION forming part of Letters Patent No. 363,696, dated May 24, 1887.

Application filed May 25, 1886. Serial No. 203,214. (No model.)

To all whom it may concern:

Be it known that I, HOMER STEWART, a citizen of the United States, residing at Beaver Falls, in the county of Beaver and State of Pennsylvania, have invented certain new and useful Improvements in Stop-Off Valves for Gas; and I do hereby declare the following to be a full, clear, and exact description of the invention, such as will enable others skilled in the art to which it appertains to make and use the same.

The invention relates to a device for automatically closing the service-pipe leading from a gas-well or a main to the place of consumption—such as furnaces, fire-places, and burners—and has for its object the construction of a simple, cheap, and reliable stop-off valve, which after having been opened positively will be so held as long as the gas is flowing under pressure, and closes automatically when the pressure is reduced below a given point or is entirely cut off.

Gas flowing from wells is subject to great variations in pressure, and it frequently occurs that the gas must be cut off from certain mains in a system on account of connections being made or repairs effected. In either instance when the mains become again filled with gas it will flow into apartments where it is to be consumed, and, mingling with the atmosphere, form a highly-explosive mixture or fluid, which will ignite as soon as a flame of any kind is kindled.

Numerous and serious accidents have resulted from the escape of gas into buildings, due largely to the fact that it is odorless, and therefore its presence cannot be detected by the sense of smell, as is the case with hydrocarbon and other artificial gas, and also to the fact that no means had been applied to the service-pipe to prevent the gas entering the building without the knowledge of the occupants.

By my invention the service-pipe is closed automatically when the pressure is withdrawn from the pipe and remains closed by the press-

ure of the gas operating on the valve when again turned on until positively opened by some person desiring to use the gas, when it will be held open as long as the pressure continues.

The invention will be hereinafter described, and particularly pointed out in the claims.

In the accompanying drawings, which form a part of this specification, Figure 1 represents a longitudinal section, and Fig. 2 a detail perspective on a reduced scale.

Reference being had to the drawings and the letters marked thereon, A represents the valve-case, made in two sections, B C, properly secured together by bolts *a*, which pass through lugs *b*. The upper section, B, has a chamber, *c*, formed in it, with an inclined top, *d*, and an inlet-passage, *e*, which communicates with a supply-pipe, as shown, and with the chamber in said section. On the rear or horizontal portion, *f*, of said section B is formed a boss or projection, *g*, provided with stuffing-box *h* and a gland or nut, *i*, for packing the rod *k*, which passes through said boss, and is provided at its inner end with a head, *l*, which corresponds with the seat *m*, formed on the inner surface of said portion *f* of section B. The outer end of the rod *k* is provided with an adjustable head, *n*, between which and the gland or nut *i* is interposed a helical spring, *o*, for holding the head *l* to its seat and out of contact with the valve while the gas is flowing through the service-pipe.

The lower section, C, is provided with a depression, *p*, into which a pipe-section, *q*, projects and forms an adjustable valve-seat at its upper end, *r*, for the valve D to rest upon, and at its rear end is formed a pocket or chamber, *s*, to receive the counterpoise of the valve. The valve D is provided with a packing, *t*, of any suitable material, which is secured thereto by a bolt, *w*, and nut *v*; or the valve may be made of a suitable metal to form a tight joint with the seat *r* without the use of packing.

E represents a counterpoise attached to or

forming an integral part of the valve, and between the valve and counterpoise is a short neck or bar, *w*, which rests upon a seat or bearing, *x*, formed on the section C, and is held 5 against lateral displacement by the projections *y y*. The weight of the valve is slightly in excess of the counterpoise E, so that it will close as soon as the pressure of the gas is cut off in the pipe leading to the valve-case, the 10 counterpoise serving to balance the valve when it is in the position shown in dotted lines in Fig. 1 and the pressure of the gas is holding it away from its seat. By applying the counterpoise to the valve and suspending it upon the narrow seat or bearing *x*, it becomes exceedingly sensitive and will yield readily to any variations of the pressure in the pipes. Furthermore, by the construction 15 shown, the friction of the working parts of the valve is reduced to the minimum and no lubricant is required to keep the parts in good working order.

The upper surface of the section C is provided with a ledge or seat, *a*, upon which the 20 projection *b* of the upper section, B, of the valve-case rests, with a gasket, *c*, of suitable material, interposed between them.

The several parts of my device having been constructed substantially as described, the 25 operation is as follows: When it is desired to turn on the gas, the rod *k* is depressed and the valve D raised from its seat *i* into the position shown in dotted lines in Fig. 1, when the counterpoise E will balance the weight of 30 the valve, and the pressure of the incoming gas, which enters the chamber *c* in the upper section, B, and impinges against the face of the valve, will hold it in said raised position as long as the gas is flowing through the pipe 35 leading to the valve-case. The rod *k* is returned to its normal position and the head *l* forced up to its seat *m* by the resiliency of the spring *o*, thus preventing any leak of gas. When from any cause the pressure in the 40 pipes is greatly reduced, or the gas entirely cut off, the valve D will fall to its seat automatically, and when the gas is again turned on in the main, or the pressure increases from the well, the gas entering the chamber *c* above the 45 valve will hold the latter securely to its seat until opened positively by the depression of the rod *k*, when the gas will flow to the place of consumption, as hereinbefore described.

It will be observed that the counterpoised 50 valve D is arranged in the path of the incoming gas, is subject to the force of its current to keep it open, and will not therefore close and cut off the supply entirely unless there be an appreciable diminution in the 55 pressure of the gas, such as would extinguish the flame at the burners wherever they may be located. In other constructions the valve is suspended in a chamber and entirely surrounded by gas in some instances and in others all but its upper surface is exposed. In either instance as soon as the pressure falls 60

the gravity of the unbalanced valve causes it to seat, much to the annoyance of the consumers.

In the constructions above referred to an effort has been made to utilize the pressure of the gas to keep the valve open; but it has been attended with very little success, for the reason that the valves are not balanced and the weight of the valves causes them to gravitate 70 to their seats as soon as the pressure becomes too light to sustain their weight. In several of these constructions the pressure of the gas is applied to hold the valve to its seat until it is raised by some positive means; but in no 75 construction known to me is the current of the gas conducted directly against the face of the valve and utilized to hold it open and the pressure of the gas applied to keep it closed.

Having thus fully described my invention, 80 what I claim is—

1. A device for automatically cutting off the flow of gas, which consists of a valve-case having an ingress and egress opening at right angles to each other, and a counterpoised valve 90 having a seat upon the egress-opening and arranged so that the pressure of the gas will hold said valve to its seat when closed and the incoming gas impinge directly against the face of the valve when open and hold it in 95 said position while the gas continues to flow, in combination with a rod for positively opening the valve, substantially as described.

2. A device for automatically cutting off the flow of gas, which consists of a valve-case having an ingress and egress opening at right angles to each other, a valve-seat in the plane of the egress-opening, a detached counterpoised valve, and a rod for positively opening the valve, the ingress-opening being in a plane 105 above the valve-seat, substantially as and for the purpose set forth.

3. A valve-case made in two sections, one of which is provided with an ingress-opening and an angular chamber or upper inclined 110 wall, the other with a valve-seat and a pocket for a counterpoise, in combination with a valve having a counterpoise attached thereto and a rod for positively opening the valve, substantially as described.

4. A valve-case made in two sections, in combination with a horizontally-counterpoised valve suspended between the valve and the counterpoise, and a rod suspended above the counterpoise for positively opening the valve, 120 substantially as described.

5. A valve-case having ingress-opening *e* and egress-opening *q* at right angles to each other, in combination with the horizontally-counterpoised valve D, seated over the egress-opening, and spring-actuated rod *k*, substantially as described.

6. A valve-case made in two sections, B C, provided with ingress and egress openings; a horizontally-suspended valve, D, having counterpoise E, a neck between the valve and the counterpoise, a bearing in the lower section 130

of the case for said neck, and a rod for positively opening the valve, substantially as described.

7. A valve-case made in two sections, one of which is provided with a chamber, *c*, having inclined wall *d* and ingress-opening *e*, the other with depression *p*, egress-pipe *q*, and pocket *s*, in combination with valve *D*, hav-

ing counterpoise *E*, and rod *h*, having head *l*, and seat *m*, substantially as described. 10

In testimony whereof I affix my signature in presence of two witnesses.

HOMER STEWART.
